UNITED STATES PATENT OFFICE.

JOHN WILLIS LOVELAND, OF LINCOLN, ILLINOIS, ASSIGNOR OF ONE-HALF TO
FREDERICK C. KOEHNLE, OF LINCOLN, ILLINOIS.

GATE.

1,235,345.

Specification of Letters Patent. Patented July 31, 1917.

Application filed December 9, 1916. Serial No. 135,984.

To all whom it may concern:

Be it known that I, JOHN W. LOVELAND, a citizen of the United States, and a resident of Lincoln, in the county of Logan 5 and State of Illinois, have invented a new and Improved Gate, of which the following is a full, clear, and exact description.

My invention relates to tilting gates, and an object thereof is to provide a simple, inexpensive and easily operable gate.

Another object of the invention is to provide a gate operable by weights arranged to vary their effect upon the gate in accordance with the position of the gate, so as to 10 eliminate shocks and wear upon the various parts of the gate mechanism.

With the above and other objects in view, the nature of which will more fully appear as the description proceeds, the invention 15 consists in the novel construction, combination and arrangement of parts as herein fully described, illustrated and claimed.

In the accompanying drawings, forming part of the application, similar characters 20 of reference indicate corresponding parts in all the views.

Figure 1 is a perspective view of a gate embodying my invention;

Fig. 2 is a vertical section on line 2—2, 25 Fig. 1.

Fig. 3 is a vertical section of the main weight housing;

Fig. 4 is a fragmentary top edge view of the gate and the post receiving it;

Fig. 5 is a fragmentary enlarged view of 30 the upper end of the gate posts; and

Fig. 6 is a horizontal section on line 6—6, 35 Fig. 4.

Referring to the drawings, 9 is the gate 40 which is hinged at one of its lowest corners 10 to a pair of gate posts 11 between which the gate is mounted to tilt on the corner 10. The posts 11 rise above the gate in normal position. The top of each post carries a 45 pair of guiding sheaves 12 mounted in a suitable frame 13 secured to the post. The gate has preferably a central vertical post 14 to which one end of a pair of flexible members 15 is secured. Each of the flexible members pass between the sheaves 12 of a corresponding post 11. It also passes over a guiding pulley 16 provided on a suitable standard 17 substantially on a level with the sheaves 12. A weight 18 is carried by 50 each of the flexible members at the stand-

ard 17. The tendency of the two weights 18 is to move the gate on its hinge between the posts 11. The two posts are preferably reinforced on their bases by braces 19.

The corner of the gate above the hinged 60 corner 10 is connected by a flexible member 20 to a weight 21 mounted to move within a housing 22 which is in the shape of a column erected in the rear of the gate. Suitable guiding pulleys 23 are provided within 65 the column for the flexible member. The weight 21 normally carries an additional weight 24 which becomes detached from the weight 21 by means of shelves or projections 25 formed within the column in the 70 path of the weight 24 when the weights 21 and 24 are set into motion by a displacement of the gate. The said shelves or projections are so located within the column 22 that the said auxiliary weight 24 loses its effect 75 upon the gate when said gate reaches the position diagonal; that is, approximately at an angle of 45° the auxiliary weight 24 loses its effect upon the gate 9. It will be noted that at substantially that position of 80 the gate the weights 18 have lost their effect upon the gate; and the further movement of the gate under the main weight 21 will be resisted partially by the weights 18, thereby preventing a rapid movement of 85 the gate to its open position under the momentum imparted to it by various weights at the start. At the moment when the weights 18 begin to resist the movement of the gate under the main weight 21 the flexible members 15 will come into contact with the sheaves 12 located near the rear end of the posts 11. Therefore the weights 18 prevent sudden shocks to the gate when it is moved from the closed to the open position.

When the gate is moved from the open position to the closed position it falls under the influence of gravity upon the gate which is resisted by the main weight 21, and its 100 movement to the closed position is facilitated by the weights 18 until it reaches an angle of 45°. At this point the auxiliary weight 24, as well as the weights 18, will begin to offer further resistance to the 105 movement of the gate under the action of gravity. It will be noted that after 45° the action of gravity upon the weight increases considerably. Therefore, this additional resistance prevents a sudden fall 110

of the gate to its normal position and thereby prevents shock and damage to the various parts of the gate, whether it is moved to the open or closed position.

5 The column 22 has a door 26 at the lower end thereof through which access may be had to the weights; and also for lubricating the lower guiding pulley 23. The column is provided with a movable head 27 whereby 10 access may be had to the auxiliary weight and also to the upper pulley 23. The stability of the hinged corner 10 of the gate is increased by extending the rod 28 on which the gate hinges to each side of the 15 gate through the bearings in the posts 11 and securing the gate corner above the hinged corner 10 to the ends of a rod 28 by suitable bracing members 29.

20 When the gate is made of wire, a special corner 30 is provided at one of the lower corners of the gate. Said corners 30 may be secured by suitable brackets 31 to the framing member 32 of the gate. Said corner has an extension or leg 33 which is to receive 25 the rod 28 on which the gate is hinged.

From the above description it will be seen that in my gate mechanism I provide a lifting weight furnished with an auxiliary weight which is adapted to retard the movement of the gate from the open to the 30 closed position, and vice versa. I further provide balancing weights which, in coöp-

erating with the retarding or auxiliary weight, eliminate jerking or jarring of the gates and, therefore, makes the mechanism 35 more durable, with less chance of disarranging the working of the gate. Furthermore, by providing a housing for the main weight, the auxiliary weights and the pulleys therefor, I protect the most important parts of 40 the mechanism from exposure to variations in atmospheric conditions, and particularly from sleet.

I claim:

In combination, a gate, gate posts, means 45 hinging the lower corner of the gate to the posts, a tubular column, a weight movable in the column, a flexible member connecting the weight to the gate above the hinge, an auxiliary weight associated with the first- 50 mentioned weight adapted to participate in the movement of the first-mentioned weight, brackets in said column for engaging the auxiliary weight for limiting its downward movement, a standard to each side of the 55 gate, a balancing weight associated with each standard, sheaves associated with the gate posts, and flexible members from the balancing weights to the gate engaging the sheaves on the posts, said flexible members 60 being connected to the gate between the ends thereof.

JOHN WILLIS LOVELAND.
